GRATE

Royce L. Beers, Birmingham, Mich., assignor to
 Detroit Stoker Company, Monroe, Mich., a corporation of Michigan

Application November 13, 1943, Serial No. 510,178

7 Claims. (Cl. 110—38)

The invention relates to grates for use in automatic stokers of that type where the fuel from a retort is fed downward over an inclined grate section to an ash discharge at the outer end thereof. It is usual to longitudinally reciprocate certain of the grate bars to facilitate the feeding of the fuel thereover and in certain constructions this reciprocatory movement is imparted to groups of individual bars. It is also usual to cool the bars by currents of air flowing on the underside thereof, the heated air being finally discharged between grate bars into the fuel bed resting thereon to support combustion.

It is the object of the invention to obtain improved means for cooling the grate bars and for controlling the discharge of the heated air through the grate.

More particularly, it is an object to obtain a construction applicable to grate bars arranged in groups. With these objects in view the invention consists in the construction as hereinafter set forth.

In the drawings:

Fig. 1 is a vertical cross section through a portion of a stoker having grates of my improved construction;

Fig. 2 is a diagrammatic end elevation of the grate sections as viewed from the retort;

Fig. 3 is a side elevation of one of the individual grate bars;

Fig. 3A is a top plan view thereof;

Fig. 3B is an end elevation;

Fig. 3C is a section on line 3C—3C, Fig. 3;

Fig. 4 is a side elevation of a companion bar;

Fig. 4A is a plan view thereof;

Fig. 4B is a cross section on line 4B—4B, Fig. 4;

Fig. 5 is a cross section through a series of bars connected together to form a group; and

Fig. 6 is a perspective view showing a small portion of the companion bars.

As illustrated in Fig. 1, A is the retort supported by a beam B resting upon a wall C. D is one of the grate sections which at its inner end is slidably supported on the retort A and at its outer end upon a beam E resting upon a wall F. G is a rockable ash discharge grate member at the outer end of the section D and H is the outer furnace wall. The wall C and a companion wall on the opposite side of the retort (not shown) enclose a central air chamber I beneath the retort and portions of the grate resting thereon. Between the walls C and F is a low pressure air chamber I' which extends beneath the greater portion of the grate.

In certain constructions heretofore used the in-

dividual grate bars have been hollow, receiving air from the high pressure chamber and discharging it into the low pressure chamber while from the latter air passes upward between the individual grate bars into the fuel bed supported thereon. Such construction is not satisfactory where a plurality of grate bars are attached to each other to form a group and I have, therefore, devised an improved and simplified construction as follows.

The grate sections D are formed of a series of grate bars J and K alternating with each other. Each of these bars has a fuel supporting top flange and a depending wall at the same side thereof so that when the two bars are placed together they will form three sides of an air channel. In the bar J the fuel supporting flange J' is imperforate but it is formed with a series of steps J² on its upper face which are substantially horizontal whereas the bar inclines downward from its inner to its outer end. The bar J has the depending flange J³. The bar K is formed with a series of projecting flanges K' constituting the fuel supporting steps but these flanges are vertically spaced and overlap each other. This will leave substantially rectangular air channels K² between the flanges K' through which air is discharged laterally into the fuel resting on the steps. The bar K also has the depending flange K³ and at its inner end a flange K⁴ forming a portion of the wall of the retort. Channels K⁵ in the flange K⁴ provide for discharge of air into the retort. Both the bars J and K are provided with bearings for engaging rock levers L which 15 impart reciprocatory movement thereto. In the bar J the bearing J⁴ which engages the lever extends laterally from the vertical flange J³ and a flange J⁵ extends from this bearing longitudinally of the bar to form a fourth wall of the air channel within the bar. At the outer end of the flange J⁵ is an upwardly inclined portion J⁶ which diminishes the space between the same and the flange J' to restrict the opening through which air is discharged. The portion J⁵ also has a depending lug J⁷ which rests upon a flange L' on the beam L thereby sealing between the high and low pressure chambers I and I'. Thus, in operation, air from the high pressure chamber passes upward into the channel formed by the top flange J⁴, depending flange J³, and flanges J⁵ and J⁶, then downward into the low pressure chamber I'. In the bar K the bearing K⁶ engages the lever and a flange K⁷ extends longitudinally to the depending lug K⁸ corresponding to the lug J⁷ of the bar J. The remainder of the length of the bar

is open at the bottom so that air from the low pressure chamber can pass upward through this opening. The air from the high pressure chamber can pass upward into the channel within the bar but a flange K^9 depending from the top flange of the bar extends near the bearing K^6 leaving only a narrow port K^{10} therebetween through which a small quantity of air can pass outward. In assembling the bars J and K to form the section D , the said bars are alternately arranged and a bolt M extending through aligned apertures in these bars clamp them together into a single unit.

With the construction as above described the section D is assembled with a series of like sections D^1 , D^2 , D^3 which extend the length of the furnace. In operation, the rock levers L impart reciprocatory movement to the sections with the adjacent sections moving in opposite directions at the same time. This will cause the feeding of the fuel from the retort downward over the grate sections and the discharging of the ash and clinker onto the rockable grate G . During this feeding movement air from the high pressure chamber I will pass upward into the spaces between the depending flanges J^3 and K^3 of adjacent bars and in the bar J will pass longitudinally between its upper flange J^4 and lower flanges J^5 and J^6 finally discharging at the outer end of the bar into the low pressure air chamber I' . In the bar K only a small quantity of air passing upward from a high pressure chamber will pass through port K^{10} but this is sufficient to cool the inner end of the bar and also to blow off any deposit that may have dropped through the openings K^2 . However, as these openings extend laterally the amount of material that can drop therethrough is quite limited. In the greater portion of the length of the bar K air passes upward from the low pressure chamber and then is discharged laterally through the ports K^2 into the fuel resting on the steps. As the air thus passing upward has previously passed through the longitudinal channel in the bar J where it has absorbed heat from both bars, it will be heated sufficiently to better support combustion.

What I claim as my invention is:

1. The combination with a grate support provided with separate chambers adapted to contain air under different pressures, of a grate on said support extending over said chambers and comprising a series of parallelly arranged grate bars of similar angle cross section, each having a fuel supporting top flange and a depending flange at one side thereof, said bars together forming a three-sided air channel beneath each top flange, and means on alternate bars for completing a fourth side of the channel extending a portion of the length of the bar through which air passes from the high pressure chamber to the low pressure chamber, the bars intermediate said alternate bars being provided with openings through the top flanges thereof forming tuyères for discharge of heated air from the low pressure chamber and channel into the fuel.

2. A grate comprising a series of parallelly arranged bars of similar angle cross section each having a fuel supporting top flange and a depending flange at one side thereof, said bars together forming a three-sided air channel beneath the top flange of each bar, and means on alternate bars for completing a fourth side to the air channel for a portion of the length of the bar to direct air longitudinally therethrough and the bars intermediate said alternate bars being provided with

openings through the top flanges thereof forming tuyères for discharge of air from the channel into the fuel.

3. A grate comprising a series of parallelly arranged inclined bars of similar angle cross section, each having a fuel supporting top flange with a series of steps in the top face thereof and a depending flange at one side of said top flange, said bars together forming a three-sided air channel beneath the top flange of each bar, and means on alternate bars for completing a fourth side to the air channel therethrough and the bars intermediate said alternate bars being provided with openings through the top flange between the steps thereof forming tuyères for discharge of heated air from the channel into the fuel.

4. A grate comprising a series of parallelly arranged inclined bars of similar angle cross section, each having a fuel supporting top flange with a series of steps in the upper face thereof and a depending flange at one side of said top flange, said bars together forming a three-sided air channel beneath the top flange on each bar, the alternate bars of the series having the successive steps thereof spaced from and overlapping each other to form air tuyères therebetween, and means on the bars of the series intermediate said alternate bars for completing a fourth side to the air channel for a portion of the length thereof to direct air longitudinally therethrough.

5. A grate comprising a unit formed of a series of parallelly arranged individual inclined grate bars, each of similar angle cross section having a fuel supporting top flange and a depending flange at one side thereof and all of said bars being secured together thereby forming a three-sided air channel beneath each top flange, the top flange of alternate bars of the series being formed of successive spaced overlapping steps with laterally discharging air tuyères therebetween, and means on the bars of the series other than said alternate bars for completing a fourth side for a portion of the length of the channel thereof whereby cooling air is directed longitudinally through said completed channel portions and will pass therefrom downward and eventually upward through the intermediate channels and tuyères communicating therewith.

6. A grate comprising a unit section formed of a series of parallelly arranged individual inclined bars each bar being of a similar angle cross section with a top portion for supporting the fuel and a depending flange at one side thereof, the top portion of alternate bars being formed by spaced overlapping flanges constituting fuel supporting steps with tuyères discharging laterally intermediate said steps, and the bars of the series other than said alternate bars each having an imperforate top flange and also being provided with a lower flange for completing a fourth side of the channel through a portion of the length thereof for directing air longitudinally through said channel, the outer end of said lower flange being bent upward to restrict the discharge passage for the air.

7. A grate comprising a unit formed of a series of connected parallelly arranged inclined grate bars each being of similar angle cross section having an upper fuel supporting portion and a depending flange at one side thereof, said bars together forming a three-sided air channel beneath each top portion, the inner ends of said bars

forming a portion of a fuel retort and being provided with tuyère openings for discharging air into the retort, each of said bars being further provided on the underside thereof with a bearing extending across the channel and adapted to engage reciprocating means, alternate bars of the series having each a flange extending from said bearing toward the outer end of the bar completing a fourth side for a portion of the length of

the air channel, said last named flange being bent upward to restrict the opening at the end of the channel, the top of said bar having its upper face formed in a series of steps, and each bar of the series other than said alternate bars having the top portion thereof formed of spaced overlapping flanges constituting fuel supporting steps with air tuyères extending laterally therebetween.
